UNITED STATES PATENT OFFICE.

EDWARD CRAIG, OF ST. JOSEPH, MICHIGAN.

BASKET MACHINE.

Application filed May 23, 1921, Serial No. 471,794. Renewed November 7, 1925.

This invention relates to machines for making receptacles, more particularly to those known as basket machines, and especially those which make what are called 5 bushel baskets, or baskets having the shape of an ordinary bushel basket, by the stapling together of strips or sections of wood veneer or other materials.

Generally stated, the object of the invention is to provide a novel and improved construction whereby receptacles of any suitable or desired character, but more especially those which are to be used as baskets, either bushel or half bushel, or of similar 10 character, may be produced in a rapid and satisfactory manner, and in a way that will tend to reduce the cost of production of said baskets or other receptacles, as well as to insure a satisfactory and comparatively high grade article, such as baskets or 15 other receptacles, from stock or materials of any suitable or desired character.

It is also an object to provide certain details and features of construction and combinations tending to increase the general efficiency and the desirability of a basket machine, or machine for making other receptacles of this particular character.

To these and other useful ends, the invention 30 consists in matters hereinafter set forth and claimed and shown in the accompanying drawings in which:

Figure 1 is a side elevation of the basket machine, embodying the principles of the 35 invention.

Figure 2 is a similar view showing the other side of said machine.

Figure 3 is a plan of the machine shown in Figure 1.

Figure 4 is a plan of the so-called web from which the baskets are made.

Figure 5 is a perspective of one of said baskets.

Figure 6 is an enlarged detail sectional view (the section being taken on longitudinal and vertical plane) of a portion of the left hand end portion of the machine, shown in Figure 1.

Figure 7 is an enlarged section on line 50 7-7 in Figure 1.

Figure 8 is an enlarged section on line 8-8 in Figure 1.

Figure 9 is an enlarged section on line 9-9 in Figure 1.

Figure 10 is an enlarged section on line 65 10-10 in Figure 1.

Figure 11 is an enlarged detail section on line 11-11 in Figure 1.

Figures 12 and 13 show perspectives of certain of the parts. 60

Figure 14 is an enlarged longitudinal sectional view of the mold and the form by which the baskets or other receptacles are made, showing the mold and the form together, with the basket between them, in 65 position to have the hoops of the baskets stapled in place.

Figure 15 is a vertical section on line 15-15 in Figure 14.

Figure 16 is a perspective of one of the 70 parts.

Figure 17 is an enlarged detail sectional view of a certain portion of the mechanism of said machine.

Figure 18 is an enlarged fragmentary and sectional plan view of a portion of the mechanism of said machine. 75

Figure 19 is a vertical section on line 19-19 in Figure 18.

Figure 20 is a vertical section on line 80 20-20 in Figure 18.

Figure 21 is a vertical section on line 21-21 in Figure 18.

Figures 22, 23 and 24 are perspectives of certain elements of the mechanism as shown 85 in Figure 20.

As thus illustrated, the invention comprises a base 1 of any suitable character, but preferably hollow, and of sufficient height to support a longitudinal shaft 2 in a suitably elevated position. This shaft extends the full length of the base and is provided at one end with a driving pulley 3 which is loosely mounted on the shaft. The drive-pulley is provided on each side of its hub with teeth 6, which are adapted to be engaged by the splines 5 and 9 of the clutch members 4 and 8 respectively. (See Figure 17).

Clutch member 8 is formed on one end of a sleeve 6^a, which has on its other end a pinion 7, and the spline or key 9 of the clutch member is mounted slidably therein and is adapted for engagement with one of the notches 6 on the adjacent side of the drive-pulley when it is desired to rotate the sleeve 6^a and its pinion 7. 100

Spline or key 5 is also slidably mounted 105

in its clutch member 4 and is adapted to engage one of the notches or teeth 6 on its side of the drive-pulley when it is desired to rotate shaft 2.

5 Said clutch members 4 and 8 are preferably controlled through the medium of a rock-shaft 10 supported in suitable bearings mounted on the base, and which extends longitudinally the full length of the base and 10 in parallel relation to shaft 2.

This rock-shaft 10 is provided with a crank-arm 37 to which is pivoted the lower end of a link 36, to the upper end 11 of which is secured a spring 12 which constantly exerts an upward pull on the link 36 with a tendency to rock the shaft 10 in the direction of the arrow shown in Figure 21. Also on the rock-shaft 10 is secured a ratchet-wheel 13 which has two teeth 14 and 15. 15 The tooth 15 is normally engaged by the end portion 16 of a hand lever 17, and this locks the shaft 10 in its normal position against the tension of the spring 12. Hand lever 17 is pivoted at 18 to swing about a horizontally and longitudinally disposed axis, and has connected thereto, adjacent its upper end, a spring 19' to hold its lower end in engagement with the ratchet-wheel 13 or with either tooth 14 and 15. 20

25 Pinion 7 operates an idler 24, and the latter in turn operates a gear-wheel 25 on the shaft 26, (see Fig. 18) and this shaft is supported in bearings 27 mounted on the main frame, and is provided with a worm 30 which engages a worm-wheel 29 mounted to rotate about a vertical axis. The worm-wheel 29 is provided with cams 30 and 35 which are adapted to alternately engage a roller 31 on one end of an arm 32 pivoted 35 intermediate its length on a horizontal transverse pivot 33 mounted in the upper end of a bracket-arm 34 fixed to the main frame. 40

45 Said cams 30 and 35 are mounted diametrically opposite on the upper face of the worm-wheel 29, and cam 30 is slightly higher than cam 35 for a purpose hereinafter mentioned.

The end of the arm 32, opposite to the end on which the roller 31 is mounted, is 50 pivotally connected to the link 36 adjacent its end portion 11, so that, as the cams 30 and 35 pass under the roller 31, the arm 32 is rocked on its pivot and pushes the link 36 downwardly and thus rotates the shaft 55 against the tension of the spring 12.

Spline or key 9 of the clutch 8 is operated into engagement with the teeth 6 by a pivoted wedge member 19, (Figs. 10 and 12) and this wedge member is operated by the rotation of the shaft 10 through the medium of the link 20 and the arm 21 secured to the shaft.

Spline or key 5 of the clutch 4 is operated into engagement with the teeth 6, on its side of the drive-pulley, by a wedge mem-

ber 38, which is similar to member 19, and this member 38 is also operated by the rotation of the shaft 10, through the medium of the link connection 39 and an arm 40 secured to the shaft 10.

70 The operation of the above described parts is as follows:—Assuming that both clutches 4 and 8 are disengaged and the drive-pulley running loosely, to start the working mechanism, hand-lever 17 is manually operated 75 against the tension of the spring 19' and this withdraws the end 16 of the lever from engagement with the tooth 15, thus releasing shaft 10 which is at once turned in the direction of the arrow shown in Figure 20, 80 by the spring 12. After this operation, the end 16 of the lever 17 will be resting against the periphery of the ratchet-wheel 13 below the tooth 15 from which it has just been released. This movement of the shaft 10 operates the link 20 and wedge 19 to cause the key 9 to engage with the drive-pulley, thus connecting the clutch-member with the driving mechanism. The rotation of the pinion 7 of the clutch-member is transmitted to the worm-wheel 29, and when it has rotated a one-half turn, cam 30 thereon engages under the roller 31, thereby tilting the lever 32, and forcing the shaft 10 to rotate against 85 the tension of the spring 12.

90 The degree of movement given to the shaft 10 through the medium of the cam 30 is sufficient to turn the ratchet-wheel 13 far enough to enable the end 16 of the lever 17 to engage with the tooth 14, and this movement of the shaft 10 withdraws the wedge 19 from the key 9 and thus allows the key 9 to disengage from the drive-pulley; and at the same time, the same movement of the shaft 10 operates the link connections 39 to 100 force the wedge 38 against the key 5 and cause it to connect with the drive-pulley and thus start the shaft 2 rotating.

105 Shaft 2 has an eccentric 41 thereon, which actuates a pawl 42 that is adapted to rotate a ratchet-wheel 43 having a cam 44 secured thereto. Cam 44 is adapted to engage a cam 45 on the hand-lever 17 with a purpose of disengaging the end 16 from the tooth 14 and thus automatically stopping the shaft 2 after it has been rotated the required number of times as will hereinafter more fully appear.

110 When the end 16 is thus disengaged from the tooth 14, the tension of the spring 12 at once rocks the shaft 10 again in the direction of the arrow shown in Figure 21, and far enough to again position the end 16 below the tooth 15, which movement withdraws clutch 4 and stops shaft 2, and again engages clutch 8 to cause the worm-wheel 115 to turn, then after a part rotation of the worm-wheel, the smaller cam 35 engages under roller 31 and the shaft 10 is again forcibly rocked against the tension of the 120

125

130

spring 12 only a sufficient distance to cause the tooth 15 to engage the end of the lever 17, or to the normal position shown in Figure 20, which is the starting position with both clutches 4 and 8 disengaged from the drive-pulley.

It is important, of course, that the rotation of the sleeve 6^a and the pinion 7 be stopped as soon as the clutch 8 is opened, and this is accomplished by means of a friction brake 46 applied to said clutch as shown in Figure 10, actuated by a lever 47 suitably connected thereto, whereby the rotation of the worm wheel 29 is accurately terminated at exactly the right time or moment, as soon as the clutch 4 is opened.

It will be seen that the worm wheel 29 serves to rotate the vertically disposed shaft 48 upon the upper end of which is secured the crank arm 49 having the boss or rounded portion 50 at its outer end.

The two standards or upright castings 51 and 52 are suitably secured upon the base 1 and spaced apart in the manner shown, the upper ends of these standards or castings being provided with guides 53, of any suitable character, for the longitudinally disposed endwise movable bar or member 54 upon the forward end of which the basket form 55 (as shown, the said form is that ordinarily used for either a bushel basket or a half bushel basket) is secured in any suitable or desired manner, but preferably by means of a spindle 56 (see Figure 14) which permits the form to rotate about a longitudinal axis during the stapling operation as will hereinafter more fully appear.

The bar 54 is provided with a transverse guide 57 which engages the boss or rounded portion 50, so that the latter moves back and forth in said guide, and while the worm wheel 29, previously mentioned, is rotating the crank arm 49 is revolving and thereby moving the basket form 55 forward, and this movement continues until the basket form arrives at the limit of its forward movement; then the rotation of the worm wheel 29 ceases, as previously explained, and the shaft 2 begins to rotate.

The hollow mold into which the form is pushed to form the basket is rigidly connected to a tubular shaft or sleeve 59 suitably supported in bearings 60 and 61 provided at the upper ends of the standards or castings 62 and 63 which are secured at their lower ends to the base 1 which forms the body frame of the machine.

Said tubular shaft 59 is provided with a spiral gear 64 which engages a similar spiral gear 65 on the transverse shaft or arbor 66, the latter being supported in suitable bearings on the body frame or stationary structure of the machine.

A ratchet wheel 67 is also mounted on the

shaft or arbor 66, to rotate the spiral gear 65, and is engaged by the dog 68 pivoted on the swinging arm 69, which latter oscillates or rocks on shaft 66 previously mentioned.

An eccentric 70 on the shaft 2 is connected by the links 71 with the end of the arm 69, so that the latter swings up and down when the shaft 2 is rotated, thus giving the spiral gear 65 an intermittent or step by step rotation, which in turn gives the spiral gear 64 a similar movement, with the result that the mold 58 is given an intermittent or step by step rotation in the desired manner.

The rod 72 which extends through the tubular shaft 59 is provided with a head 73 for engaging the bottom of the basket (see Figure 14), and is provided at its other end with a cross arm 74 which slides in the tubular guides 75 suitably supported on the body frame of the machine.

Springs 76 in said tubular guides exert a constant pull on the cross arm 74, so that the head 73 exerts a yielding pressure against the bottom of the basket, thereby depressing the bottom portion of the web shown in Figure 4 into the hollow 77 shown in the bottom of the form 55, thereby to properly form the basket.

The rotation of the basket between the form and the mold, by the rotation of the shaft 2 and the intermittent action of the ratchet mechanism 67 and 68, as stated, is for the purpose of enabling the stapling mechanism to secure the hoops 78 and 79 to the basket (see Figure 5), and the said stapling mechanism, while it may be of any suitable or desired character, is preferably constructed and arranged as shown, and comprises two pairs of staplers 80 of any suitable construction. These four staplers are carried by the arm 81 which is secured to the upper end portion of the vertically reciprocating member 82, the latter being arranged to slide up and down in the guide 83 mounted on the body structure.

This vertical reciprocation of the staple drivers and formers (not shown) of said staplers, in the usual well known manner, is preferably produced by the eccentric 84 on the shaft 2 through the medium of the pitman 85 thereof, which pitman is connected to the lower end of the vertically reciprocating member 82, whereby the two staplers are operated in unison. The said staplers, of course, are provided with feeding devices 86, of any suitable character, to feed the wire from which the staples are made, and this feed mechanism is operated in a manner that will be readily understood, by the pitman 87, which latter is connected at its lower end to the eccentric 870 on the shaft 2, whereby the rotation of this shaft serves to reciprocate the two staplers to insert the staples into the hoops and slats or

strips of the web shown in Figure 4, after the latter is shaped or formed between the basket form 55 and the mold 58, in the manner explained.

The hoops of the basket are fed into position, in any suitable or desired manner, by means of devices adapted for this purpose, such as the one shown in Figure 16 of the drawings. As thus illustrated the device 10 for feeding the hoops comprises a body 88 pivoted on the machine frame at 89 to tilt freely about a horizontally and longitudinally disposed axis, having portions 90, 91, 92 and 93 which guide the hoops into position below the staplers, in the manner shown in Figure 15, each device having a spring 94 secured to its hook 95 at one end and to the hook 96 on the casing of the staplers at the other end. With this construction, therefore, the body 88 of each device is free to tilt in order to accommodate itself to the movements of the hoops while the latter is being pulled into place by the rotation of the basket form and mold, it being understood that each hoop is inserted by hand far enough to permit its end portion to be anchored by the first staples, and after that the step by step or intermittent rotation of the basket, in the manner explained, serves to pull the hoop forward and bend it automatically around the basket, staples being inserted at intervals along each hoop to secure it in place.

In Figure 14, for example, the two hoops 78 and 79 are shown inserted in position below the two staplers, and the basket web is shown bent into position to have the hoops stapled thereto. As explained, the body 88 of each device for feeding hoops can tilt freely while the hoops are being drawn intermittently through the guides and into position to be stapled to the basket.

A stationary guard 97 is preferably arranged in the position shown, being of annular form, disposed in position to supplement the basket mold 58 in bending the web, as shown in Figure 14, but the guard 97 is supported in stationary position by the rods 98, and does not rotate with the basket. The curved support 99 is provided immediately below the guard 97, and is adapted to support the lower edge of the web when the latter is placed in position against the edge of the guard 97 and it is in this way that the web is supported in position to receive the forward pressure of the basket form 55 when the latter moves into the mold.

The support 99 is preferably secured to the upper ends of the rods 100, which latter are secured in any suitable or desired manner, as by the nuts 101 screwed thereon, to the base or body frame 1 of the machine.

With a view to always promptly stopping the shaft 2, so that the staplers will be

stopped in their elevated positions, a band brake 102, of any suitable character, is applied to the shaft 2 at any convenient point in the length thereof. This brake is operated by a lever 103 to the outer end of which a link 104 is connected, and this link is connected to a short lever 105 which is fulcrumed on the shaft 10 previously mentioned. A spring 106 is connected to the lower end of the lever 105, and the tension of this spring is exerted to operate the band brake 102 so that the latter exerts sufficient friction to prevent the shaft 2 from rotating after the clutch 4 is opened, thus stopping the stapling devices and the rotary mold in their normal positions.

Thus, in general, the operation of the machine for the purpose of forming the web into basket form, and of thereafter stapling the hoops in place, is as follows. The web is placed on the support 99 as previously explained. Then the hand lever 17 is pulled outward to start the forward movement of the basket form 55, as previously explained. The form 55 moves forward to force the web into the mold 58, in the manner shown in Figure 14. This having been done, the rotation of the crank shaft 48 is stopped, as previously explained; so that the form 55 is left in position in the mold. The rotation of the shaft 2 is then started, and the staplers are operated and the mold 58 is rotated, as explained, so that the basket is slowly rotated in a step by step manner below the staplers, and the hoops are inserted and then stapled in place in the manner explained. As soon as the stapling operation is finished, the clutch 4 is automatically opened, in the manner previously explained, and the clutch 8 is again closed, thus stopping the rotation of the shaft 2 and at substantially the same time starting the rotation of the shaft 48, whereby the form 55 is pulled out of the basket and returned to normal position.

The tension of the springs 76 exerted through the rod 72, and through the head 73 against the bottom of the basket, serves to automatically push the basket a distance out of the mold 58, so that the basket is dislodged from its tight fit in the mold, thus clearing the machine for the conversion of another web into a basket. It will be understood, of course, as previously indicated, that the entire machine is stopped as soon as the form 55 is returned to its normal position (which is the position shown in Figure 1) so that the hand lever 17 must be operated each time it is desired to make a basket.

The staplers 80, as previously explained, may be of any suitable character, but are, as stated, preferably four in number, there being one pair of each hoop, the members of each pair being arranged in tandem, so

that for each downward stroke of the arm 81 two staples are driven in each hoop. The two staples are spaced the desired distance apart, in a circular row on each hoop 5 and the feeding action of the spiral gearing by which the basket is rotated intermittently is such that the basket is turned or moved sufficiently each time to receive the staples, so that the staples of each hoop are 10 spaced apart the desired distance around the basket,—that is to say, two staples are first driven in the hoop, and then two more, so that all four of them are located at equidistant points in the circumference of 15 the hoop. This is continued, of course, until the other end of the hoop is lapped over and secured upon the end which was first secured in place. Thus a multiple head stapler is provided over each hoop, 20 and consequently four staples are driven simultaneously. This materially increases the capacity or output of the machine, as the hoops are applied in about half the time formerly consumed in performing this 25 operation in an automatically controlled basket machine.

With further reference to the prompt stopping of the rotation of the sleeve 6^a and the pinion 7 it will be seen that the lever 30 47 can be operated in any suitable or desired manner. Preferably, however, as a matter of further and special improvement, this lever is operated by a bell crank 107 pivoted on the side of the frame member 35 52 and controlled by a spring 108 which tends to hold the lever in normal position. When the slide 54 moves backward the guide 57 strikes the upper end of the lever 107 and causes the latter to tilt about its 40 pivot 109 and thereby depress the outer end of the lever 47 and thus tighten the band brake 46 to stop the rotation.

As a matter of still further improvement 45 the pivoted member 38 has a somewhat greater throw or extent of movement than the member 19, to shift the latch 5 a little farther and more promptly in closing the clutch which controls the transmission of power to the staplers, as this clutch carries 50 a greater load than the other clutch, inasmuch as it requires more power to drive the staplers than to operate the other parts of the machine; and hence, as stated, the clutch having the latch 5 must start promptly and 55 the latch must be practically fully shifted in order to avoid the danger of breakage, such as might occur if the latch were only slightly shifted and only had partial engagement upon the starting of rotation to 60 operate the staplers; and, therefore, the links 39 are so proportioned and connected together that the cam member 38 has a greater throw or range of movement than the member 19, when the rock shaft 10 is 65 rocked, thus insuring a somewhat quicker

and more positive action for the clutch which controls the transmission of power to the staplers, than for the other clutch, for the reasons explained.

The cam or device which automatically 70 stops the machine, such as the cam 35 previously described, is preferably removable so that the machine can operate either intermittently or continuously—that is to say, with this cam in place, or with any provision for automatically stopping the machine in the manner previously described, the machine will be automatically stopped after the completion of each basket; but, by removing said cam or device the machine 75 will continue in operation after the basket is completed, and the operator or attendant will quickly drop another web into place, at the proper time, and the second basket will be produced without stoppage of the 80 machine between the two baskets; and thus, by rendering inoperative the means for automatically stopping the machine, baskets can be made one after the other without any 85 stoppage of the machine until after the 90 required number has been made. Continuous operation of the machine in this way will materially increase the capacity or output of the machine, and with a fairly skilled operator and materials of a fairly 95 good quality the machine can be run continuously hour after hour; but, when necessary or desirable, the automatic stopping device can be applied, and in this way the 100 machine can be automatically stopped after the completion of each basket. Of course, when the automatic stopping device is not used, then the starting and stopping of the machine can be controlled in any suitable or desired manner.

It will be seen that the staplers of the 105 stapling mechanism (see Figure 9) are so arranged that the two staples driven each time in each hoop are so spaced apart that the curvature of the curved row of staples 110 does not interfere with the parallel insertion of the two staples thus driven simultaneously in each hoop, each time said mechanism is operated, thereby insuring the desired or necessary insertion of the staples 115 in the manner explained. In other words, each operation of the stapling mechanism results in the driving of a pair of staples in each hoop, and the members of each pair are parallel, instead of being radially inserted. Now, if the members of each pair 120 of staples were too far apart, or were as far apart as they might be on a perfectly flat surface, difficulty would be encountered in the insertion of the two staples in the curved hoop, as the wider apart the staples are the greater the tangent of each staple and the greater the angular insertion thereof through the hoop. So far as the basket 125 itself is concerned, radial insertion of the 130

staples would be desirable, but difficulties would then be encountered in the construction and operation of the staplers, and in the construction and operation of the machine itself the parallel arrangement of the staple drivers and the parallel insertions of the four staples driven each time is preferable. Hence, as stated, the two staples of each pair driven each time in each hoop are such a distance apart that the curvature of the hoop does not interfere with the proper insertion of the staples parallel in the manner stated. The rotation of the basket form and mold, with the basket therein, can be of a step by step nature to insure the proper spacing of the staples, and in fact all of the different elements of the machine are combined and correlated in a manner to insure their co-operation for the driving of the staples in the manner shown and described. The driving of two staples simultaneously in each hoop, to form a curved row of properly spaced staples, in the making of baskets of this kind, is different from the previous practice, of course, which involved the driving of only one staple at a time in each hoop, and for the carrying out of this new method the different elements of the machine must be properly correlated and timed in their operations with reference to the driving of two staples simultaneously, in each hoop, whereby the basket is fully stapled in practically half the time previously necessary for this operation, and is given only one-half the number of step by step movements or partial rotations necessary to insure the proper driving of the staples. The staples are driven, it will be seen, in a manner to form a circular row of staples in each hoop, so that there is a continuous or unbroken row of staples extending entirely around the basket on each hoop, when the basket is finished.

With the novel combination and organization shown and described, it will be seen that each and every staple is driven slantingly or obliquely through the hoop of the basket, instead of being driven straight through at right angles to the thickness of the hoop, which latter would be true if the staples were driven radially instead of tangentially of the axis of the true circular row in which they are located. Thus all of the elements are organized and co-ordinated and arranged to co-operate with each other to insure proper insertion of the staples, obliquely and tangentially, in the manner stated, whereby each basket is made in much less time than was heretofore necessary with machinery of this kind involving a separate operation of the stapling mechanism for each and every staple driven in the basket hoop.

As plainly shown in Fig. 9 of the draw-

ings the double stapling mechanism, comprising the two staplers 80 arranged side by side, is disposed in position to insert the two staples parallel in the manner described. It will be seen that the vertical line between the two staplers is in the vertical plane of the axis of rotation of the basket forming and holding means, which axis is coincident with the axis of the shaft 59 by which the mold is rotated. Thus the pressure of the stapling mechanism, or the staple driving pressure, is balanced at opposite sides of the axis of rotation of the basket, whereby the staples are driven in pairs, and the pressure of the insertion of one staple of each pair in the basket is balanced at the opposite side of said axis by the pressure of insertion of the other member of the same pair. In other words, the two staples of each pair are driven parallel in vertical planes at opposite sides of the vertical plane of the axis of rotation, and each and every pair is driven in this manner. This not only results in the insertion of each staple obliquely through one of the hoops, tangentially of a circle the axis of which is coincident with said axis of rotation, but also results in balancing the pressure of the stapling mechanism on the rotary form and mold, so that each operation of the stapling mechanism is in the nature of a balanced pressure on the basket, whereby such pressure does not tend to rotate the basket about the fixed axis of rotation thereof. Thus, instead of driving staples radially, one at a time, in a round basket mounted to rotate about a fixed axis, which would have no tendency to rotate the basket, the stapling mechanism and other elements are so relatively arranged that two staples are driven simultaneously in each hoop in a manner to balance the pressure at opposite sides of the axis of rotation. Thus, as explained, the number of stapling operations is greatly reduced, but at the same time each plurality of staples is so inserted that each staple is driven obliquely through its hoop, and in such a manner that the driving pressure is balanced at opposite sides of the axis of rotation, whereby there is no tendency to rotate the basket about its axis, notwithstanding the tangential insertion of the staples. As shown, the two staples which are driven simultaneously in each hoop are spaced apart a distance which is not too great for the purposes of the basket, and such a distance that the tangential insertion of the staples obliquely through the hoop is not rendered difficult by the curvature of the hoop, as the hoop is of considerable diameter while the distance between the two staples is much less. The intermittent rotation of the basket, in a step by step man-

ner, is so adjusted or regulated, as shown and described, that the distance between successive pairs of staples, or the spacing between successive pairs of staples, is substantially the same as the distance between each pair, so that the staples are preferably spaced uniformly throughout the circumference of each circular row of tangentially driven staples. Assume a small circle 5 concentric to the axis of rotation, the diameter of which circle is equal to the distance between the two simultaneously driven staples of each pair, and it will be found that one member of each parallel row of 10 staples is tangential to one side of said circle, while the other member is tangential to the other side of said circle, whereby the space between the members of each 15 pair of simultaneously driven staples is 20 radial to said axis of rotation. Thus one member of each pair is inserted on a line passing at one side of the axis of rotation, while the other member of each pair is inserted on a line passing at the opposite 25 side of said axis, whereby the driving and insertion pressure of one staple tends to counterbalance the pressure of the other member of the same pair, when the two 30 staples are thus inserted simultaneously in the hoop. Thus constructed and operated, the machine necessarily involves the grouping of the staple forming and driving instrumentalities in pairs, one pair for each 35 hoop of the basket, with the driving members of each pair located parallel and tangential to the opposite sides of a circle the axis of which is coincident with the axis of the basket while it is rotating. As 40 shown in Fig. 9, the diameter of this circle is approximately the same as the diameter of the hub shown at the center of the rotary form 55, upon which the basket is held while being stapled.

As shown, the four wire feed devices 45 are all disposed on the shaft 860, and the latter is actuated by the ratchet device 861 operated by the pitman 87 previously mentioned. In this way, the four wire feed devices are actuated simultaneously to simultaneously feed four wires to the four staplers. As the staplers are mounted in pairs, one 50 pair over each hoop of the basket, it follows that the distance between the staplers at the hoop feeding side of the machine and their allotted wire feed devices is greater 55 than the distance between the staplers at the other side and their allotted wire feed devices. Thus, the two hoop strips are caused to feed simultaneously, each below a pair 60 of staplers, in the direction in which the basket rotates, whereas the four wires fed from the other side must necessarily feed in the opposite direction. Thus, the four 65 staplers must all be adapted to receive wire from the same side of the machine.

What I claim as my invention is:

1. In a basket making machine, the combination of a mold to receive the bottom of the basket, stapling mechanism above said mold, a rotary and reciprocating form 70 to be pushed into said mold, means to rotate the mold and form with the basket between them during the operation of said stapling mechanism, and stationary means extending beyond the mold in the direction 75 of said form, with the edge of said stationary means adjacent the edge of the mold when the basket is in position, and means for feeding hoops below said mechanism and between the basket and said stationary means, so that the hoops are covered by said stationary means during the making of the basket. 80

2. A basket-making machine comprising 85 stapling means, a mold, a form, and means for alternately, intermittently rotating the mold, and reciprocating said form, involving a shaft extending longitudinally of the machine, a clutch to rotate said shaft, a sleeve on said shaft, a clutch to rotate said sleeve, a rock shaft provided with means for controlling said clutches, a ratchet wheel on said rock shaft, a hand lever normally engaging a tooth of said ratchet wheel, a spring to maintain said hand lever in engagement with said ratchet wheel, a spring to rock said rock shaft in one direction when said hand lever is manually actuated, thereby to close one clutch and rotate said sleeve, gearing operated by said sleeve, means operated by said gearing to reciprocate said form, means operated by said gearing to turn said rock shaft in the opposite direction, thereby to open the one clutch and close the other, in order to stop the rotation of said sleeve and start the rotation of said longitudinally extending shaft, means operated by said longitudinally extending shaft to automatically actuate said hand lever, thereby to again reverse the clutches and automatically return the form to normal position, and means for automatically causing the actuation of said rock shaft, and the stopping of the machine, when said form reaches normal position. 118

3. In a machine for making receptacles from suitable materials, the combination of a mold rotatable about a fixed axis, a form to force the materials into said mold, adapted to rotate therewith to form a basket with a circular rim curved about said axis, mechanism for performing successive operations on the materials, cooperating with said form and mold to insert staples obliquely in said materials, disposed in position to form a plurality of circular rows of staples in the receptacle and operative for simultaneously inserting a plurality of parallel staples in each row, tangentially of a circle the axis of which is coincident with 120 125 130

- said axis of rotation, thereby balancing the pressure of said mechanism at opposite sides of said axis, devices to automatically and intermittently rotate the mold and the form 5 during the operation of said mechanism to successively present different portions of the materials to the action of said mechanism in such a manner that the total number of staples for the receptacle is at least 10 four times the total number of operations of said mechanism, and operable to uniformly space the successive staples of each row on the circular rim portion of the basket, wire feed means at one side of said 15 mechanism to feed wire for all of the staples, hoop strip guide means at the other side of said mechanism, to feed hoops to receive the staples, whereby all the hoop strips are fed from one side by rotation of 20 the basket, while all the wire is fed from the opposite side, whereby for each hoop strip feeding from one side of said mechanism there is a plurality of wires feeding from the opposite side, means to permit 25 axial movement of the form toward and away from the mold, and instrumentalities whereby said form moves forward to co-operate with said mold in shaping the receptacle, remains in the forward position 30 thereof to rotate with the mold during the operation of said mechanism, whereby to ensure the driving of the staples in the manner stated, and automatically returns to normal position upon the completion of the 35 receptacle, the machine thus constructed and operated necessarily involving the grouping of the staple forming and driving instrumentalities in pairs with the driving members thereof parallel and tangential to the opposite sides of said circle. 40
4. In a basket machine, the combination of a base, a rotary mold supported on said base, a reciprocating form supported on said base, adapted to rotate with said mold 45 about a longitudinal axis, stapling mechanism arranged to operate on the basket to form a circular row of staples each driven obliquely to the work around the outside of the basket and operative for inserting successive pluralities of simultaneously driven parallel staples in said row, with said mechanism disposed in position to insert the staples tangentially of a circle the axis of which is coincident with said axis of rotation, thereby balancing the pressure of said mechanism at opposite sides of said axis, and with the staples of each plurality so spaced apart that the curvature of the row does not interfere with the parallel insertion of the staples in each group, wire feed means at one side of said mechanism to feed wire for all of the staples, hoop strip guide means at the other side of said mechanism, to feed hoops to receive the staples, whereby all the hoop strips are fed in the direction of rotation of the basket, while all the wire is fed from the opposite side, whereby for each hoop strip feeding from one side of said mechanism there is a plurality of wires feeding from the opposite side, a longitudinally disposed shaft in said base, means on said shaft to operate said stapling mechanism, means operated by said shaft for rotating said mold, a sleeve on said shaft, means operated by said sleeve to reciprocate said form, and instrumentalities for controlling the rotation of said shaft and said sleeve to space the successively driven groups of staples, the machine thus constructed and operated necessarily involving the grouping of the staple forming and driving instrumentalities in pairs with the driving members thereof parallel and tangential to the opposite sides of said circle, and means on said shaft to operate said wire feed means. 75 80 85
5. In a basket machine, the combination of means to present the basket materials in position to have a circular hoop bent around and secured thereto, stapling mechanism for driving a plurality of staples at a time in said hoop, at different points circumferentially thereof, to form a circular row of staples each driven obliquely through said hoop, with the staples of each plurality spaced apart a distance substantially the same as the distance between one plurality and the next, and with said mechanism disposed in position to insert the staples tangentially of a circle the axis of which is coincident with the axis of said hoop, thereby balancing the pressure of said mechanism at opposite sides of said axis, wire feed means at one side of said mechanism to feed wire for all of the staples, hoop strip 90 95 100 105 110 115 120 125 130
- guide means at the other side of said mechanism, to feed hoops to receive the staples, whereby all the hoop strips are fed in the direction of rotation of the basket, while all the wire is fed from the opposite side, whereby for each hoop strip feeding from one side of said mechanism there is a plurality of wires feeding from the opposite side, and means to rotate the basket intermittently about said axis during the operation of stapling the hoop in place thereon, so that the basket moves a sufficient distance each time to receive the plurality of staples, the machine thus constructed and operated necessarily involving the grouping of the staple forming and driving instrumentalities in pairs with the driving members thereof parallel and tangential to the opposite sides of said circle. 120
6. In a basket machine the combination of stapling mechanism disposed in position to insert staples obliquely in the work, tangentially of a circle concentric to the basket, reciprocating and rotating forming means to support the basket while being 130

- stapled, cooperating with said mechanism to form a plurality of circular rows of successively inserted pluralities of staples, wire feed means at one side of said mechanism 5 to feed wire for all of the staples, hoop strip guide means at the other side of said mechanism, to feed hoops to receive the staples, whereby all the hoop strips are fed in the direction of rotation of the basket, while 10 all the wire is fed from the opposite side, whereby for each hoop strip feeding from one side of said mechanism there is a plurality of wires feeding from the opposite side, and means for rotating said forming 15 means about the axis of said circle, thereby balancing the pressure of said mechanism at opposite sides of said axis, the machine thus constructed and operated necessarily involving the grouping of the staple forming and 20 driving instrumentalities in pairs with the driving members thereof parallel and tangential to the opposite sides of said circle.
7. In a machine for making baskets by stapling hoops to the outside thereof, the combination of means for holding the basket in position, stapling mechanism disposed in position for simultaneously driving a plurality of staples obliquely in said hoops, tangentially of a circle concentric to the basket, 25 instrumentalities for causing relative movement between the basket holding means and said stapling mechanism, thereby to cause said hoop to be bent around the basket in circular form, wire feed means at one side of said mechanism to feed wire for all of the staples, hoop strip guide means at the other side of said mechanism, to feed hoops to receive the staples, whereby all the hoop strips are fed in the direction of rotation of the basket, while all the wire is fed from the opposite side, whereby for each hoop strip feeding from one side of said mechanism there is a plurality of wires feeding from the opposite side, and means for actuating said mechanism during said relative motion, thereby to form a circular row of staples around the outside of said hoop, with the members of each plurality of staples spaced apart a distance to prevent the curvature of the circular hoop from interfering with the parallel insertion of the members of each plurality of staples, and said mechanism and basket holding means being relatively disposed to balance the staple driving pressure at opposite sides of said axis, and to cause each staple to be inserted obliquely in said hoop, the machine thus constructed and operated necessarily involving the grouping of the staple forming and driving instrumentalities in pairs with the driving members thereof parallel and tangential to the opposite sides of said circle.
8. In a basket machine, the combination of means for feeding parallel strips to form hoops, work supporting means for bending 30 said strips to form circular hoops in parallel planes, so that the hoops are formed about an axis common thereto, mechanism disposed in position for simultaneously driving a plurality of parallel staples in each hoop, tangentially of a circle concentric to said axis, thereby balancing the pressure of said mechanism at opposite sides of said axis, whereby each staple is inserted obliquely in the hoop, the hoop feeding 35 means being all at one side of said mechanism, wire feed means at the other side of said mechanism to feed wire for all of the staples, whereby for each hoop strip feeding from one side of said mechanism there is a plurality of wires feeding from the opposite side, and means for causing relative movement between said hoops and said mechanism to form a circular 40 row of staples on each hoop, with the successive pluralities of staples properly spaced apart to make the row practically continuous on each hoop, and with the members of each plurality spaced near enough together to prevent the curvature of the hoops 45 from interfering with the parallel insertion of the staples of each plurality, the machine thus constructed and operated necessarily involving the grouping of the staple forming and driving instrumentalities in pairs with the driving members thereof parallel and tangential to the opposite sides of said circle.
9. In a basket making machine requiring intermittent rotation of the basket during the making thereof, the combination of mechanism to drive a plurality of staples each time the basket stops between rotations, wire feed means at one side of said mechanism to feed wire for all of the staples, hoop strip guide means at the other side of said mechanism, to feed hoops to receive the staples, whereby all the hoop strips are fed in the direction of rotation of the basket, while all the wire is fed from the opposite side, whereby for each hoop strip feeding from one side of said mechanism there is a plurality of wires feeding from the opposite side, basket holding means, a spiral gear axially alined with said means for the rotation thereof, a shaft disposed at right angles with said axis, a spiral pinion on said shaft to engage said spiral gear, a ratchet wheel on said shaft, a ratchet dog to engage 50 said ratchet wheel, and means to actuate said ratchet dog back and forth to intermittently rotate the basket, all cooperating and timed to cause each said plurality of staples to be driven in the manner stated.
10. In a machine for making baskets by stapling hoops on the outside thereof, the combination of stapling mechanism for simultaneously driving a plurality of staples in each hoop, devices for rotating the basket about the axis of the hoops, hoop strip guide 55

means all disposed at one side of said mechanism to feed hoop strips below said mechanism in the direction of rotation of the basket, wire feed means at the other side of said mechanism to feed wire for all of the staples, whereby for each hoop strip feeding from one side of said mechanism there is a plurality of wires feeding from the opposite side, and instrumentalities 10 for automatically controlling and timing the feeding of the wire and the driving of the staples and the rotation of the basket.

11. A structure as specified in claim 10, said mechanism comprising two staplers for 15 each hoop, so that four staples are driven by each operation of said mechanism, said hoop stripe guide means being disposed in position to guide a hoop strip below each pair of staplers, and said wire feed means com-

prising a longitudinally disposed shaft having 20 four wire feed devices thereon, one for each stapler, and means for operating said shaft to simultaneously feed wire to all of the staplers, the distance between the two 25 staplers at the hoop feeding side of the machine and their allotted wire feed devices being necessarily greater than the distance between the staplers at the other side and their allotted wire feed devices.

12. A structure as specified in claim 10, 30 said mechanism comprising four parallel and vertically disposed staplers, two for each hoop, whereby four parallel staples are inserted by each operation of said mechanism, with each staple extending tangential- 35 ly of a circle within the basket.

EDWARD CRAIG.
